(57) **CLAIM**

The ornamental design for a toy toothbrush set, as shown and described.

DESCRIPTION

FIG. 1 is a front, right and top perspective view of the first part of the toy toothbrush set, showing my new design;
FIG. 2 is a rear, left and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof;
FIG. 8 is a bottom plan view thereof;

FIG. 9 is a front, right and top perspective view of the second part of the toy toothbrush set;

FIG. 10 is a rear, left and bottom perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof;

FIG. 16 is a bottom plan view thereof;

FIG. 17 is a front, right and top perspective view of the third part of the toy toothbrush set;

FIG. 18 is a rear, left and bottom perspective view thereof;

FIG. 19 is a front view thereof;

FIG. 20 is a rear view thereof;

FIG. 21 is a left side view thereof;

FIG. 22 is a right side view thereof;

FIG. 23 is a top plan view thereof;

FIG. 24 is a bottom plan view thereof;

FIG. 25 is a front, right and top perspective view of the first part and second part assembled together of the toy toothbrush set;

FIG. 26 is a rear, left and bottom perspective view thereof;

FIG. 27 is a front view thereof;

FIG. 28 is a rear view thereof;

FIG. 29 is a left side view thereof;

FIG. 30 is a right side view thereof;

FIG. 31 is a top plan view thereof;

FIG. 32 is a bottom plan view thereof;

FIG. 33 is a front, right and top perspective view of the first part and third part assembled together of the toy toothbrush set;

FIG. 34 is a rear, left and bottom perspective view thereof;

FIG. 35 is a front view thereof;

FIG. 36 is a rear view thereof;

FIG. 37 is a left side view thereof;

FIG. 38 is a right side view thereof;

FIG. 39 is a top plan view thereof;

FIG. 40 is a bottom plan view thereof; and,

FIG. 41 is a front view of three parts of the toy toothbrush set.

The broken lines shown in the drawings illustrate portions of the toy toothbrush set that form no part of the claimed design.
